UNITED STATES PATENT OFFICE.

ALBERT WEWETZER, OF ELGIN, ILLINOIS, ASSIGNOR TO ILLINOIS WATCH CASE COMPANY, OF ELGIN, ILLINOIS, A CORPORATION OF ILLINOIS.

DESIGN FOR A WATCH BRACELET.

Application filed March 21, 1929. Serial No. 30,577. Term of patent 3½ years.

To all whom it may concern:

Be it known that I, ALBERT WEWETZER, a citizen of the United States, residing at Elgin, in the county of Kane and State of Illinois, have invented a certain new, original, and ornamental Design for a Watch Bracelet, of which the following is a specification, reference being had to the accompanying drawing, forming part hereof, in which—

Fig. 2 is a fragmentary edge view thereof, showing my new design.

I claim:

The ornamental design for a watch bracelet, as shown.

ALBERT WEWETZER.
